TELEPHONE BOOTH

Henry Dreyfuss, South Pasadena, Calif., and Donald Genaro, Fort Lee, and Douglas H. King, Short Hills, N.J., assignors to Bell Telephone Laboratories, Incorporated, New York, N.Y., a corporation of New York

Filed Feb. 12, 1960, Ser. No. 59,382

Term of patent 14 years

(Cl. D13—1)

FIG. 1

FIG. 2

FIG. 1 is a front perspective view of a telephone booth showing our new design; and

FIG. 2 is a front perspective sectional view of the lower portion of FIG. 1.

The side not shown is like the side shown and the rear is substantially plain.

The dominant features of our design reside in the portions shown in full lines.

We claim:

The ornamental design for a telephone booth, as shown and described.
